LADY'S STOCKING

Oscar E. Schletter, Lansdale, Pa.

Application March 18, 1952, Serial No. 18,954

Term of patent 14 years

(Cl. D47—7)

To all whom it may concern:

Be it known that I, Oscar E. Schletter, a citizen of the United States and a resident of Lansdale, county of Montgomery, State of Pennsylvania, have invented a new, original, and ornamental Design for a Lady's Stocking, of which the following is a specification, reference being had to the accompanying drawing, forming part thereof.

In the drawing—

Figure 1 is a front elevational view of a lady's stocking with the central portion broken away, embodying my design; and

I claim:

The ornamental design for a lady's stocking, as shown.

OSCAR E. SCHLETTER.
